UNITED STATES PATENT OFFICE.

CHARLES S. PILLSBURY AND LIGE S. SIMS, OF PULASKI, VIRGINIA.

LIFTING JACK.

Application filed August 1, 1921. Serial No. 488,887.

To all whom it may concern:

Be it known that we, CHARLES S. PILLSBURY and LIGE S. SIMS, citizens of the United States, residing at Pulaski, in the county

5 of Pulaski and State of Virginia, have invented certain new and useful Improvements in Lifting Jacks; and we do declare the following to be a full, clear, and exact description of the invention, such as will enable others skilled in the art to which it ap-

10 pertains to make and use the same.

This invention relates to an improved lifting jack which is especially, although not necessarily, designed for use in car shops, 15 repair yards, and at points along railroad tracks where repairs are made on passenger and freight cars, the same being especially advantageous for placing the car coupling heads in alinement for quick and easy cou-

20 pling.

The principal object of the invention is to generally improve upon lifting jacks by the provision of one of extreme simplicity and durability which may be effectively em- 25 ployed for hoisting extremely heavy loads in the minimum amount of time.

Another object of the invention is to provide a novel jack of this class embodying inner and outer telescoping lifting members 30 which are simultaneously elevated at relatively different speeds, permitting the jack to be placed in operative position in much less time than is ordinarily required by jacks of similar construction.

35 A further object of the invention is to provide a jack embodying rack and pinion means for operating the hoisting members, said pinions being mounted on a shaft and said shaft having a binding or brake de- 40 vice associated therewith for holding it against rotation, whereby the hoisting members may be held in various elevated positions to which they have been moved without accidentally slipping or dropping.

45 A still further object of the invention is to provide a jack embodying a rotatable base with radial feet designed to be supported on the cross-ties, the particular construction employed enabling the base and 50 feet to be readily and properly positioned for effective engagement with said ties regardless of the position of the couplers.

Other objects and advantages of the invention will be apparent during the course 55 of the following description.

In the accompanying drawings forming a part of this specification and in which like numerals are employed to designate like parts throughout the same:

Figure 1 is a front elevational view of a 60 lifting jack constructed in accordance with this invention showing the hoisting members in inoperative position.

Figure 2 is a central vertical sectional view through the jack showing the internal 65 construction more clearly.

Figure 3 is a horizontal sectional view taken substantially on the plane of the line 3-3 of Fig. 2.

Figure 4 is a detail sectional view showing the hoisting members in raised position.

Figure 5 is a sectional view taken substantially on the plane of the line 5-5 of Fig. 4.

Figures 6 and 7 are detail sections taken substantially on the planes of the lines 6-6 75 and 7-7 respectively of Figs. 2 and 1 respectively.

Broadly speaking, the invention contemplates the provision of a novel jack embodying a standard and inner and outer telescoping hoisting members designed to be simultaneously moved to operative position at relatively different speeds, thus enabling them to be very quickly moved to effective position. Ordinarily, jacks embodying telescoping sections are so constructed that one of said sections is raised to its limit and the other section is then successively raised to the desired position. Such construction takes much more time than is required to 90 place our jack in operative position.

Referring to the drawings by numerals, 1 designates a substantially cylindrical hollow standard in which similarly shaped and constructed telescoping inner and outer hoisting members 2 and 3 respectively are vertically slidable. In order to accomplish the desired results, the standard is formed at one side near its upper end with a slot 4 through which a relatively large pinion 5 100 is extended, the latter being engageable with a rack bar 6 on the inner hoisting member 2. This pinion 5 is keyed or otherwise fixedly mounted on a horizontal rotating shaft 7 journaled in spaced bearing lugs 8 105 and 8^a extending outwardly from the standard on opposite sides of the slot. This shaft is permitted to slide through its bearings and in addition to carrying the large pinion, has keyed thereon two smaller pinions 9 110

which are positioned for co-operation with a pair of rack-bars 10 on the outer hoisting member 3 and are spaced from the bearing lugs. All of these pinions are simultaneously rotated and it will thus be seen that the hoisting members will be simultaneously lifted. However, as before indicated, the different sizes of the pinions will cause the inner hoisting member 2 to be elevated much faster than the member 3. It may be stated here that the member 2 in order to accommodate the large pinion 5 and rack bar 6 is formed with a groove 11, while the member 3 is flattened as indicated at 12 on the same side, this construction serving to permit connection of the rack-bars 10 to said flattened portions. The standard 1 is bulged as indicated at 13 to accommodate the rack-bars 10. As previously indicated, the invention embodies means for maintaining the shaft 7 in a stationary position, that is, this means serves to prevent sliding movement of the shaft and also to prevent rotation. The means referred to can better be seen in Figs 1 and 3. Reference being had to these figures it will be seen that the bearing lug 8^a is equipped with a screw-threaded bushing 14 and a portion of this bushing extends beyond the bearing lug. The bushing is prevented against rotation by means of a set screw 14^a which passes into the bearing lug and into a socket formed in the bushing. Arranged on the extended screw-threaded portion of the bushing is a manually rotated binding element 15 including a handle 15^a and a substantially conical friction surface 16 which is designed for co-action with an abutment 16^a fixedly mounted on the shaft 7 and held on the latter by means of a nut 17 which is in turn held in place by means of a cotter pin 17^a. Referring now to the other end of the shaft, it will be seen that a friction collar or device 15^b is bolted or otherwise secured to the adjacent bearing lug and an abutment 16^b is fixed on the adjacent extended end of the shaft and is designed for co-action with this part 15^b. The collar 16^b is likewise fixedly mounted on the shaft 7 and is held against displacement by means of a nut and cotter-pin bearing the same reference characters given those previously mentioned. Above it was pointed out that the smaller pinions are both spaced from the inner surfaces of the lugs 8 and 8^a. Consequently, by grasping the handle 15^a of the device 15 and rotating it on the screw-threads of the aforesaid bushing, it will be seen that it will come into engagement with the collar 16^b and impart a sliding movement to the shaft 7 and will thus bind the adjacent small pinion 9 against the bearing lug 8. Hence, the shaft 7 cannot then be rotated. It is obvious that when the parts 15 and 16^a are brought into engage-

ment with one another, the parts 15^b and 16^b are simultaneously engaged with one another. Inasmuch as the pinions 5 and 9 are keyed on the shaft, it will be seen that they will be held against rotation and the telescoping sections of the shaft can thus be locked in any desired position. 70

To assist in preventing possible rotation of this shaft, I employ a pair of spring-pressed dogs 20 pivoted on the standard and co-operative with the small pinions 9. It is obvious that these dogs permit rotation of the pinions in but a single direction. When it is desired to rotate said pinions in an opposite direction, the dogs are manually disengaged from the pinions and swung up against the standard. It is to be noted that flat springs 21 are associated with the dogs and are anchored at both ends on the latter, being bowed adjacent their inner ends so that when the dogs are swung to ineffective position, they will be held by these springs in said position. 75

For the purpose of imparting rotation to said pinions, I employ a relatively small and additional pinion 22, which is mounted on a shaft 23 journaled in bearing lugs 24 on the standard 1. Attention may here be directed to the fact that this shaft is manually rotated by means of a detachable crank handle 25 fitted on the squared end 26 of said shaft. It may be pointed out here that the hoisting member 2 is equipped on its upper end with a swivelled cup-shaped detachable seat 27 which is particularly advantageous when used in connection with car couplers. 90

After the inner hoisting member 2 is raised to a predetermined height, it is desirable to lock it in the position to which it has been moved. This result is partially accomplished by the aforesaid brake. However, I make use of additional means for use in conjunction with this brake. The means referred to comprises a plurality of circumferentially spaced pivoted spring-pressed latches 28 carried by the member 3, and automatically projectable through openings 29 in this member. Referring to Fig. 4, it will be seen that pins 30 serve 95 as pivots for these latches. However, when the hoisting member 2 is in raised position and supporting a heavy load, it is desirable to take all strain off of these pins to prevent breakage thereof. To this end, the bearing openings 31 in the latches are made sufficiently large to permit said latches to rest on the bottoms of the openings 29 rather than be directly supported by the pivot pins 30. This construction places the weight 100 and strain on the hoisting member 3 instead of causing the pivot pins to partially support the load. It may be pointed out here that the standard 1 is formed with external depressions 28^a which serve to provide clear- 105

105

ance spaces for the aforesaid latches, permitting free movement of the latter.

The jack in addition to including the parts already described, comprises, as before indicated, a rotary base, preferably in the form of a ring 32, rotatable in a groove 33 in the lower end of the standard 1. The standard in addition to being formed with this groove 33 is formed with continuous counter-groove 34 into which the reduced ends of set-screws 35 extend, it being obvious that by moving the set screws, the base can be held in any desired position. The ring 32 carries a plurality of spaced radial feet 36 designed to rest on the cross ties to prevent possible tilting of the jack. This particular kind of base including the feet will be found extremely advantageous when used along railroad tracks, since it can be effectively supported on the cross ties at the desired point.

The operation of the jack is as follows:

Assuming that the parts are in the position disclosed in Figures 1 and 2, it will be seen that by grasping the hand-grip of the crank-handle 25 and rotating the same, the shaft 7 and the pinions thereon will be rotated. In so doing, the hoisting members 2 and 3 will be quickly raised to the desired position. It is to be noted as before indicated, that these members will be simultaneously raised, but the member 2 will be raised much faster than the member 3 because of the difference in size of the pinions which co-act with the rack-bars on these members. Hence, little or no time will be required in placing the jack in operative position. When the hoisting member 2 is elevated sufficiently high to uncover the latches 28, the springs which are associated with the same will project them through the openings 29 so that they will become engaged with the lower end of this member and in conjunction with the brake means retain the member in the position to which it has been moved. A continued rotation of the shaft 7 will continue to elevate the members until the desired height has been reached. The spring-pressed pawls or dogs 20 will prevent accidental reverse rotation of the pinions during the raising of the hoisting elements. However, as before stated, by raising these dogs upwardly and against the body of the standard, free rotation of the pinions will be permitted in the opposite direction. This is only done when the jack is being lowered to ineffective position. As before pointed out, the particular type of dogs and springs employed will serve to retain the dogs in such effective position without any special means or without manually holding them in said position. It may be added here that by operating the brake means of shaft 7 in the manner heretofore set forth, the shaft can

be held against possible rotation and the telescoping sections thus held in set position. This binding means will be found especially advantageous when it is found necessary to lower the hoisting elements after the dogs have been disengaged from the pinions with which they co-operate. It is obvious that if these dogs were disengaged, and the weight is on the hoisting members, they would drop suddenly and possibly cause breakage. However, by making use of the improved binding means, this condition of affairs is prevented. It is hardly necessary to again point out that the rotary base and feet can be properly positioned for effective engagement with the cross ties or any other suitable support and that the rotary seat on the upper end of the hoisting member 2 can be properly positioned for effective engagement with the car coupler or other element being raised. In order to disengage the latches from the inner hoisting member, it will be necessary to raise both hoisting members, until the latches which are carried by the member 3, are positioned about the upper edge of the standard. Then, by pressing the fingers against the latches, the latter can be disengaged and the hoisting member be permitted to move down.

The foregoing description taken in connection with the drawings is sufficient to enable persons skilled in the art to which the invention relates to obtain a clear understanding of the same and to make note of the various advantages and features of the invention. In view of this, a more lengthy and detailed description is deemed unnecessary.

Since probably the best results may be obtained with the construction and arrangement herein shown and described, this is taken as a preferred embodiment of the invention. However, slight minor changes coming within the scope of the subjoined claims may be resorted to.

We claim:

1. A jack comprising a standard, hoisting members slidably supported on said standard, said members being equipped with rack bars, a shaft rotatably mounted on the standard, pinions mounted on said shaft and having their teeth engaged with the teeth of said rack bars, one of said pinions being larger than the other, whereby to simultaneously elevate the hoisting members at relatively different speeds.

2. A jack embodying a standard having a slot in one side near its top, hoisting members slidably mounted on said standard, rack bars secured to said members, one of said bars being disposed opposite said slot, a rotary shaft mounted on the standard, large and small pinions connected to said shaft, one of said pinions extending through

- the aforesaid slot and being engageable with the teeth on the rack bar opposite said slot, the other pinion being engaged with the remaining rack bars so that when the shaft is 5 rotated, the pinions will simultaneously elevate the hoisting members at relatively different speeds.
3. A jack comprising a hollow standard having a slot on one side near its top, being also equipped on opposite sides of this slot with bearing lugs, inner and outer telescoping hoisting members slidably arranged in said standard, rack-bars on said members, one of said bars being positioned 10 opposite said slot, a shaft journaled in said bearings, one large and two small pinions fixedly mounted on said shaft, said large pinion extending through the aforesaid slot and being engageable with the ratchet teeth 15 on the rack-bar opposite this slot, the other pinions being engaged with the remaining rack-bars, whereby when the shaft is rotated, the pinions will simultaneously elevate the hoisting members at different speeds.
4. A jack comprising a hollow standard, inner and outer telescoping hoisting members slidably arranged in said standard, rack-bars on said members, a shaft rotatably mounted on said standard, pinions fixedly 20 mounted on said shaft and engageable with said rack-bars, one of said pinions being sufficiently larger than the other to cause the hoisting members to be simultaneously lifted at different speeds with respect to one another.
5. A lifting jack including a standard having bearing lugs thereon, a shaft rotatably and slidably mounted in said bearings, gearing fixed on said shaft between the lugs, 25 being spaced from the inner faces of the latter, and means on said shaft for imparting sliding movement thereto and binding said gearing against one of the lugs for holding the shaft against rotary movement.
6. A lifting jack embodying a gear carrying shaft rotatably and slidably mounted on the standard, and brake means associated with said shaft for assisting in preventing it from rotating and for moving it longitudinally, said brake means embodying an abutment secured on one end of the shaft and an adjustable binding device which is associated 30 with the abutment to obtain a friction lock and to impart sliding movement to the shaft.
7. A lifting jack embodying a standard having spaced bearing lugs arranged thereon, a horizontally disposed shaft rotatable and slideable in said bearings, abutments on the opposite ends of said shaft beyond said 35 bearings, friction devices between said bearings and said abutments with which the latter are engaged, one of said devices being adjustable for bringing said abutments and devices into tight frictional engagement with one another.

8. The structure set forth in claim 7, wherein hoisting gears are secured on the intermediate portion of said shaft between said lugs, whereby when the adjustable friction device is actuated, one of said gears will 70 be brought into tight frictional engagement with the adjacent lug.

9. A lifting jack comprising a standard, a hoisting device slidably engaged therewith, said device having ratchet teeth, said standard being equipped with spaced bearing lugs, a shaft rotatably and slidably mounted in said bearings, a pinion fixedly mounted on said shaft and co-operable with said ratchet teeth, an abutment on one end of the shaft, 80 and an adjustable binding device associated with said abutment for engaging the latter and imparting a sliding movement to the shaft whereby to bind said pinion against one of the bearing lugs to prevent rotation 85 of the shaft.

10. A lifting jack comprising a standard, a slidably hoisting device associated therewith and provided with teeth, bearings carried by said standard, a shaft rotatably and slidably 90 mounted in said bearings, a gear carried by said shaft and co-operable with said teeth, an externally screw-threaded bushing carried by one of said bearings, a binding device mounted on said bushing, and an abutment on the shaft co-operable with said binding device for frictionally engaging said gear with one of said bearings for preventing rotation of the shaft.

11. The structure set forth in claim 10 together with binding means on the opposite end of the shaft which is simultaneously operated when said binding device is rendered effective.

12. A jack embodying a plurality of telescoping members, the intermediate member being provided in its wall with an opening, a spring-pressed latch arranged in said opening and held in ineffective position by the inner member and capable of being projected to support the inner member, said latch being provided with a comparatively large bearing opening, and a pin extending crosswise of the aforesaid opening, said latch being journaled on the pin and the bearing opening being of sufficient diameter to relieve the pin of direct excessive strains as set forth.

13. A lifting jack comprising a hollow standard having a slot formed in one side near its top, pairs of upper and lower bearing lugs arranged on opposite sides of said slot, inner and outer telescoping hoisting members slidably arranged in said standard, rack bars on said members, one of said bars being positioned opposite the aforesaid slot, horizontally disposed shafts journaled in the bearings of the aforesaid lugs, said shafts being disposed in spaced parallelism, one large and two small pinions fixedly secured 125

on the upper shaft, said large pinion extending through the aforesaid slot being engageable with the rack teeth on the bar opposite the slot, the other pinions being engaged 5 with the remaining rack bar so as to simultaneously lift the hoisting members at relatively different speeds, a small pinion fixed

on the lower shaft and meshing with the aforesaid large pinion, and a hand crank for rotating said last named shaft.

10

In testimony whereof we have hereunto set our hands.

CHARLES S. PILLSBURY.
LIGE S. SIMS.
